HANDGRIP FOR A MOTION PICTURE CAMERA OR SIMILAR ARTICLE

Grant D. Ross, Jr., Chicago, Ill., assignor to Bell & Howell Company, Chicago, Ill., a corporation of Illinois

Filed Oct. 29, 1964, Ser. No. 82,384

Term of patent 14 years

(Cl. D61—1)

FIG. 1 is a perspective view of a handgrip for a motion picture camera or similar article showing my new design;

FIG. 2 is a side elevational view of the same;

FIG. 3 is a front elevational view of the same; and

FIG. 4 is a bottom view of the same.

The dominant feature of my design resides in the combination, on the handgrip disclosed, of the tapered, substantially rectangular sections throughout the grip portion, support post, and mounting surface in conjunction with the area of contrasting surface appearance on the grip portion, all as shown.

The broken-line showing of a camera in FIG. 1 is for illustrative purposes only.

I claim:

The ornamental design for a handgrip for a motion picture camera or similar article, as shown and described.
